(57) **CLAIM**

The ornamental design for an engraving machine, as shown and described.

DESCRIPTION

FIG. 1 is a front elevational view of a first component of an engraving machine, shown separately for ease of illustration;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevational view of a second component of the engraving machine, shown separately for ease of illustration;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view thereof;

FIG. 16 is another perspective view thereof;

FIG. 17 is a front elevational view of a third component of the engraving machine, shown separately for ease of illustration;

FIG. 18 is a rear elevational view thereof;

FIG. 19 is a left side elevational view thereof;

FIG. 20 is a right side elevational view thereof;

FIG. 21 is a top plan view thereof;

FIG. 22 is a bottom plan view thereof;

FIG. 23 is a perspective view thereof;

FIG. 24 is another perspective view thereof

FIG. 25 is a front elevational view of a fourth component of the engraving machine, shown separately for ease of illustration;

FIG. 26 is a rear elevational view thereof;

FIG. 27 is a left side elevational view thereof;

FIG. 28 is a right side elevational view thereof;

(Continued)

FIG. 29 is a top plan view thereof;
FIG. 30 is a bottom plan view thereof;
FIG. 31 is a perspective view thereof;
FIG. 32 is another perspective view thereof;
FIG. 33 is a perspective view of the engraving machine where the engraving machine is in a configuration of use; and,
FIG. 34 is another perspective view thereof.
